UNITED STATES PATENT OFFICE.

ROBERT H. DOWLING, OF NEWARK, OHIO, ASSIGNOR OF TWO-THIRDS TO CHARLES FOLLETT AND CHARLES H. FOLLETT, BOTH OF SAME PLACE.

CAR-COUPLING.

SPECIFICATION forming part of Letters Patent No. 414,146, dated October 29, 1889.

Application filed July 27, 1889. Serial No. 318,920. (No model.)

To all whom it may concern:

Be it known that I, ROBERT H. DOWLING, a citizen of the United States, and a resident of Newark, in the county of Licking and State of Ohio, have invented certain new and useful Improvements in Car-Couplings; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a perspective view of the invention. Fig. 2 is a similar view, the draw-head and hook being separated. Fig. 3 is a bottom plan view. Figs. 4 and 5 are details, respectively, of the locking-pin and guide-rod.

This invention relates to certain improvements in hook car-couplings; and it consists in the novel construction and combination of parts, as hereinafter set forth.

In carrying out my invention, I employ a draw-head A and a coupling-hook or knuckle-hook B, which is held and pivoted between bearings in the end or head of the draw-bar. The end or head of the draw-bar indicated at C is enlarged laterally and of a general semicircular form, terminating at one forward corner in an oblique outward and forward extending arm a, and at other forward corner portions in the rounded bearings a', which engage the concave shoulder of the knuckle-hook. The cavity b of the head of the draw-bar is made tapering vertically from the broad seat between the bearings a' to the arc-shaped end b', which extends from the throat c' outward to the root of the horn or arm a. The bearings a' are provided on the inner sides with the angular stops c, which are located on the forward and inner portions of the rounded bearings a', as shown, and engage the semicircular trunnion ends of the knuckle-hook, limiting its movements. These angle-stops form the forward and inner portions of the recessed trunnion-bearings c', which are open at their outer forward portions, as at c'', to admit the semicircular trunnion of the knuckle-hook between said angular stops and

the curved tapering outer guard-wall of the draw-head indicated at a''.

In the upper and lower walls of the draw-head are the bearings d d' for the locking-key D, these bearings being formed with a small offset d'', which extends entirely through the lower bearing and but partially through the upper bearing. The locking-key D is provided with an offset or stop e at the lower end, and above this offset it is cylindrical. The key is pivoted to the slide-rod E, which is located in bearings obliquely in rear of said key at one corner of the throat of the draw-head, and when detached from said slide-rod can be removed from the draw-head by pulling it down through the lower aperture. The end of the guide-rod indicated at e projects downward below the lower surface of the draw-head sufficiently to enable the brakeman to unlock the coupling by an upward blow upon the lower end of said guide-rod by a flat angle-operating rod attached underneath the car and extending to the side of the same, this action driving upward the guide-rod and the locking-key connected to the upper end thereof; or, if preferred, said guide-rod, with its flat-ended angle-arm used for operating the same, can be dispensed with, and an angle operating-rod, extending along the end of the car to the side thereof and attached by a small chain to the top of the locking-key D, may be used to operate said locking-key D from the side of the car, and a stud may be provided at the side of the car near said angle-rod to hold said angle-arm in raised position to prevent a coupling being made, if desired.

To the lower surface of the draw-head at one side near the rounded bearing portion is a stud f, which carries a spring g. The knuckle-hook B consists of the broad hook portion F and the oblique-tapered pressure-arm G, which joins the hook portion at the concave bearings h, which are formed by shoulders of said hook portion. This pressure-arm stands at an angle of about forty-five degrees to the hook, projecting therefrom backward and inward toward the throat of the draw-bar. Its forward face k is convex and projects from the cavity of the draw-head when the hook is open as far as the corner portions of said draw-head, serving to re-

- ceive the impact of the hook of the opposite draw-head when two cars are being coupled, and thereby forcing the hook into locked position. The rear edge of the pressure-arm is 5 rounded at its juncture with the hook-head to form a portion of the trunnion *l*, which engages the back bearing of the draw-head, and said rear portion is provided with an offset or lug *m*, which engages an offset recess *m'* 10 in the back of the cavity of the draw-head when the hook is closed in, and strengthens its engagement, the guide-rod of the locking-key engaging the lug *m*, and when the key is down holding the pressure-arm securely between 15 said guide-rod and key, which extends through an aperture or seat *n* in said pressure-arm. From the upper portion of this seat *n* extends in the upper surface of the pressure-arm an arc groove *n'*, which, when 20 the locking-key is raised, serves to release the pressure-arm and allow the hook to open outward in uncoupling. The upper and lower tapered surfaces of the pressure-arm extend from its point to the concave shoulders of the hook, and are provided at their junction with 25 said concave shoulders with the semicircular trunnion ends *p*, which extend backward and slightly inward from said concave shoulders, as shown.
- 30 The lower portion of the hook-head is provided with a lug *s'* to engage the spring *g* of the lug *f*, whereby it is designed to cause the knuckle-hook to open out automatically when the locking-key is raised to its disengaged position.
- 35 It will be observed that the pivotal portions of the knuckle-hook have their stepped bearings facing inward, while the stepped bearings of the draw-head face outward in such a 40 manner that the tapered pressure-arm and its trunnion can be readily slipped into position in the cavity of the draw-head. When the locking-key and its guide-rod are placed in position and the spring *g* put in engagement, the coupling is in operative condition. 45 The edge of the hook-head is notched and perforated usually, as shown, to facilitate its connection with the ordinary link-and-pin coupling when necessary.
- 50 Having described this invention, what I claim, and desire to secure by Letters Patent, is—
- 55 1. The hook car-coupling having an automatically-opening hook provided with an arc groove, in combination with the locking-

key having an offset or stop at its lower end, the lower end of said key when elevated engaging said groove, substantially as specified.

2. The hook car-coupling having a spring-actuated automatically-opening hook, in combination with the locking-key, and the guide-rod having a laterally-extended upper end 60 connected to the upper end of said key, substantially as specified.

3. The hook car-coupling having a spring-actuated hook, in combination with the locking-key and its uncoupling and guide rod, 65 substantially as specified.

4. In a hook car-coupling, the hook locking-key provided with a detachable uncoupling and guide rod projecting below the draw-head, substantially as specified.

5. In a car-coupling, the combination, with a draw-head having stepped bearings facing outward in its cavity or chamber, and having 75 on their inner sides angular stops, of the knuckle-hook having its concave shoulder-bearings and trunnion-bearings facing inwardly to engage the bearings of said draw-head, said trunnion ends being engaged by 80 said angular shoulders, substantially as specified.

6. In a car-coupling, the draw-head having the oblique horn and rounded bearings oppositely disposed at the sides thereof, and the 85 knuckle having the concave shoulder-hook portions, and the oblique convex edge-pressure arm extending backward and inward therefrom, in combination with a locking-key, substantially as specified. 90

7. In a car-coupling, the combination, with the draw-head having the oblique horn and rounded bearings oppositely disposed, of the knuckle having the concave shoulder-hook and tapered pressure-arm extending inward 95 at an angle of forty-five degrees therefrom, the locking-key, its guide-rod, and opening-spring, substantially as specified.

8. In a car-coupling, the combination, with the draw-head having the stepped bearings 100 and tapered cavity, of the concave-shouldered knuckle-hook, having the tapered perforated and grooved pressure-arm, the locking-key, and its guide-rod, substantially as specified.

In testimony whereof I affix my signature in 105 presence of two witnesses.

ROBERT H. DOWLING.
